UNITED STATES PATENT OFFICE.

WILLIAM A. FARRAR, OF WHITMAN, MASSACHUSETTS.

MICROMETER-GAGE ATTACHMENT FOR LATHES, &c.

No. 796,903

Specification of Letters Patent.

Patented Aug. 8, 1905.

Application filed March 13, 1905. Serial No. 249,876.

To all whom it may concern:

Be it known that I, WILLIAM A. FARRAR, a citizen of the United States, residing at Whitman, in the county of Plymouth and Commonwealth of Massachusetts, have invented new and useful Improvements in Micrometer-Gage Attachments for Lathes, &c., of which the following is a specification.

My invention relates to improvements in radius-micrometers. It is designed to be used in connection with lathes, milling-machines, &c.

In the drawings herewith accompanying and making a part of this application, Figure 1 is a central vertical sectional view of my improved device, taken on a line passing through the center of the micrometer and its holder; and Fig. 2 is an end view of the same.

Same letters of reference refer to like parts.

It consists of a suitable holder A, adapted to be supported in a lathe or other machine in any convenient way, as by means of sockets B, into which take the holding-points of a lathe. (Not shown.) At a convenient point in one side of the holder a recess C' is formed, the bottom of the recess being substantially in line with the centering-sockets. Mounted in the holder in any convenient manner is a micrometer comprising a hollow supporting-case C and a spindle D, threaded at the top to engage a similar thread on the inside of the case C. The spindle projects downwardly through the case and through a guiding-nut D', which screws into the lower end of the case C, the whole being positioned so that the spindle D projects into the recess C'. The holder A has an upwardly-extending tubular portion O, with one or more slits O' therein. Said tubular portion is surrounded by a ring P, which is held in place by a set-screw P' passing through the ring and engaging the external surface of the tubular portion. An annular flange R on the supporting-case C engages the upper edge of said tubular portion and limits the down-

ward movement of the supporting-case in the holder.

The structure *per se* of the micrometer forms no part of my invention.

In operation the holder, with the micrometer attachment, is mounted between the holding-points of the lathe and the spindle adjusted relative to the centering-points, so that the distance the spindle projects below the centering-points will equal the desired diameter of the article to be turned. The cutter-head or milling-tool having been adjusted to a position coincident with the end of the spindle, the centering-holder is removed and the article to be worked is placed in position.

My improved device is especially advantageous in lining up lathe-centers to bring them into parallelism with ways of the lathe, in determining the difference in height or detecting wear in lathe-bearings, in setting lathe-tools by micrometer measurement to turn or bore any required diameter, in lining up work on lathe-carriages, and generally in testing the accuracy of machine-tools—such as lathes, milling-machines, upright drilling-machines, &c.

Having thus described my invention and its use, I claim—

A device of the character described comprising a holder having centering-sockets in the ends thereof and a recess in the side intermediate the ends thereof in combination with a micrometer-gage mounted upon said holder at right angles thereto, the spindle on the micrometer passing through the holder into the recess therein.

In testimony whereof I have signed my name to this specification, in presence of two subscribing witnesses, this 9th day of March, 1905.

WILLIAM A. FARRAR.

In presence of—

GEO. D. SOULE,

FRANK W. BRYANT.
